UNITED STATES PATENT OFFICE.

ALBERT MARTIAN GRAVES, OF McCLEARY, WASHINGTON.

SIRUP PITCHER.

Application filed January 10, 1924. Serial No. 685,451.

To all whom it may concern:

Be it known that I, ALBERT M. GRAVES, citizen of the United States, residing at McCleary, in the county of Grays Harbor 5 and State of Washington, have invented certain new and useful Improvements in Sirup Pitchers, of which the following is a specification.

The present invention relates to improvements in sirup pitchers.

An object of the invention is to improve the construction of sirup pitchers and to provide a simple, inexpensive and efficient one adapted to catch the drippings and conduct the same back to the interior of the pitcher, and to thereby prevent sirup from accumulating on the exterior of the pitcher.

Another object of the invention is to provide a structure of this nature which is reliable in use and well adapted to the purpose for which it is designed.

With the above and numerous other objects in view as will appear as the description progresses, the invention resides in certain novel features of construction, and in the combination and arrangement of parts as will be hereinafter more fully described and claimed.

In the drawing:

Figure 1 is a vertical section through the pitcher embodying my invention, and

Figure 2 is a top plan view thereof with the same in an open position.

Referring to the drawing in detail it will be seen that 1 designates the body of the pitcher to which is hinged a lid 2. The upper edge of the body 1 is provided with an inwardly curved flange 3 which preferably extends around about one side of the head and is disposed at its forward side. A sleeve 4 is mounted in the body 1 so as to extend above its upper end. This sleeve is tapered inwardly toward its upper end so that the diameter of its upper end is smaller than that of its lower end. The lower end of the sleeve is flared outwardly so as to form a channel flange 5 provided with a series of openings 6 situated adjacent the rear side of the pitcher preferably. This channel 5 terminates in a ring 7 which is riveted or otherwise fastened to the body as at 8. It is to be noted that the inwardly extending flange 3 on the body 1 overhangs a portion of the channel flange 5 of the sleeve 4.

When the sirup is poured from the

pitcher out through the sleeve 4 it will be seen that the drippings will be caught in the channel flange 5 and will flow back into the interior of the pitcher through openings 6. Because of the slow flowing of sirup there will often be some collected on the channel flange 5 and especially when the sirup pitcher is being frequently used on the table and the inwardly disposed flange 3 will prevent surplus sirup getting out of the pitcher or on the exterior thereof.

Although I have described my invention with a certain degree of particularity it is to be understood that numerous changes in the details of construction in the combination and arrangement of parts may be resorted to without departing from the scope or spirit of the invention as hereinafter claimed or sacrificing any of its advantages.

Having thus described my invention what I claim as new is:

1. In a sirup pitcher of the class described, a body provided at its upper end with an inwardly curved flange adjacent its forward side and a sleeve disposed in the body so as to extend above its upper end, said sleeve being tapered inwardly toward its upper end, its upper edge being closer to the center of the pitcher than is the edge of the flange, said sleeve being flared outwardly at its lower end to provide a channel flange having a series of openings therein adjacent the rear side of the pitcher, and a ring formed on the channel flange and fixed to the body of the pitcher.

2. In a sirup pitcher of the class described, a body having an inwardly extending flange disposed on the forward portion of its upper edge, a sleeve tapered toward its upper end so as to have its upper edge closer to the center of the pitcher than is the edge of said flange, said sleeve being flared at its bottom end to provide a channel flange having a series of openings therein adjacent its rear portion, and means for fixing the sleeve to the interior of the body so that the channel flange is disposed below the inwardly extending flange of the body.

3. In a sirup pitcher of the class described, a body, a sleeve disposed in the upper end of the body so as to terminate above the upper edge thereof, said sleeve tapering toward its upper end and flared at its bottom end to provide a channel flange having a series of openings therein adjacent its rear portion, a ring depending from the outer

periphery of the channel flange and fixed to the interior of the body, the upper edge of said body provided with an inwardly curved flange adjacent its forward portion so as 5 to overhang the channel flange of the sleeve and so that its inner edge is spaced farther from the center of the pitcher than is the upper edge of the sleeve.

4. In a sirup pitcher of the class described, a body provided at its upper end with an inwardly extending curved flange,

and a sleeve disposed in the body extending beyond the upper end thereof and tapered inwardly toward its upper end so as to have its upper edge disposed closer to the center 15 of the pitcher than is the edge of the flange.

In testimony whereof I affix my signature in presence of two witnesses.

ALBERT MARTIAN GRAVES.
